US00D877774S

(12) **United States Design Patent** (10) Patent No.: **US D877,774 S**
(45) Date of Patent: **** Mar. 10, 2020**

(54) **DISPLAY SCREEN OR PORTION THEREOF WITH GRAPHICAL USER INTERFACE**

(71) Applicant: **Lutron Technology Company LLC**,
Coopersburg, PA (US)

(72) Inventors: **Manisha Dahiya Baluja**, Lansdale, PA
(US); **John N. Callen**, Center Valley,
PA (US); **Erica L. Clymer**,
Northampton, PA (US); **Sanjeev
Kumar**, Harleysville, PA (US); **Mark
Law**, Bethlehem, PA (US); **Christopher
Spencer**, Coopersburg, PA (US)

(73) Assignee: **Lutron Technology Company LLC**,
Coopersburg, PA (US)

(**) Term: **15 Years**

(21) Appl. No.: **29/689,489**

(22) Filed: **Apr. 30, 2019**

Related U.S. Application Data

(63) Continuation of application No. 29/657,781, filed on
Jul. 25, 2018, now Pat. No. Des. 848,476, which is a
continuation of application No. 29/603,036, filed on
May 5, 2017, now Pat. No. Des. 825,611, which is a
continuation of application No. 29/553,804, filed on
Feb. 4, 2016, now Pat. No. Des. 789,416.
